UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

WALL CONSTRUCTION.

Application filed December 9, 1922. Serial No. 605,871.

My invention relates to improvements in the wall construction of frame buildings provided with an exterior plaster finish, and has for one of its objects the provision of grille brackets for securing the plaster reinforcing grille or lathing in an outstanding manner to the wall sheathing, preparatory to the application of the plastic material; a further object is the provision of a grille bracket comprising a spacing element carried on a nail and operatively slideable along thereon for coacting with the nail head for confining the reinforcing grille therebetween; a still further object is the provision of a spacing element normally locked against movement on the lower end of the nail but operatively slideable thereon for engaging and holding the reinforcing grille against the lower side of the nail head when the nail is driven a proper distance in the wall sheathing; a still further object is the provision of a spacing element formed of a length of wire coiled around and on the nail and having an extension on the upper coil for retaining the reinforcing grille on said coil whereby the nail head will engage and hold the reinforcing grille on the coil when the nail is driven in the wall sheathing.

With the foregoing still further objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed without departing from the spirit of the invention.

40 In the drawings—

Figure 1 is a face view of a portion of the wall of a building constructed in accordance with my invention, with the plastic material omitted;

45 Figure 2 is a side elevation of one of the grille brackets with the spacing element disposed in its normal position at the lower end of the nail, engaging a fragmental section of the reinforcing grille;

50 Figure 3 is a vertical sectional view of the bracket as shown in Fig. 2;

Figure 4 is a view in elevation of the grille

bracket showing the spacing element disposed at the upper end of the nail;

Figure 5 is a view of the bracket in its permanent position attached to the wall sheathing;

Figure 6 is a view in elevation looking in the direction indicated by the arrow "a" in Fig. 4.

Figure 7 is a vertical sectional view of the bracket as illustrated in Fig. 6.

Figure 8 is a cross section on line 8—8, Fig. 6.

Figure 9 is a cross section on line 9—9, Fig. 6.

Figure 10 is a cross section on line 10—10, Fig. 6.

Figure 11 is a plan view of the preferred form of the bracket, and a section of the grille.

Figure 12 is a plan view of a modified form of the bracket, and a section of the grille.

In the preferred form of the invention, the lateral dimensions of the head of the nail are restricted, relative to the spacing element, so that the head will seat upon the grille wire when the nail is projected downwardly through the spacing element as far as it can go and in which manner it is adapted to assist the extension on the upper end of the spacing element to hold the grille against the body thereof.

In the modified form, the lateral dimensions of the nail head are relatively increased so that the head will seat upon the extension of the spacing element and thereby assist it to hold the grille against the spacing element.

Referring to the drawings in detail, throughout which like reference characters designate like parts—

The numeral 1 designates the usual siding or wall sheathing secured to the frame-work of those portions of the walls of frame buildings intended to be provided with an exterior coating of plastic material, which are preferably laid tight-jointed and of uniform thickness so as to present a reasonably smooth outer surface for the reception of building paper 2, which is preferably disposed between the sheathing boards 1 and plastic material 2'.

The application of the paper 2 is to prevent any moisture contained in the plastic material, or chemical action of the plaster, from penetrating the boards and warping or otherwise detrimentally affecting them.

Over the sheathing boards 1 and exteriorly of the paper 2 is stretched a wire grille 3, which may consist of suitable network of wire. In the present instance the grille consists of ordinary chicken-wire embodying a plurality of wires 4 inter-twisted at 5, thereby forming open meshes 6.

7 designates a grille bracket, which comprises an ordinary nail embodying a shank portion 8 provided with the usual disk-shaped head 9, and a spacing element 10 embodying a plurality of wire coils 11 embracing the lower part of the shank 8 and terminating upwards in an extension 12.

20 The coils 11 are intended to embrace the shank 8 with sufficient contractile tension so as to become normally locked thereon against accidental movement in any direction, and the extension 12 is intended to be in the 25 form of an outwardly and upwardly extending curve having sufficient radius so that the wires 4 either single or in twisted pairs may be readily inserted between the extension 12 and the nail.

20 After the grille 3 has been stretched over the paper 2, I prefer to apply the bracket 7 by projecting the forward end thereof through one of the meshes 6 and disposing the shank 8 so as to engage one side of one 35 of the wires 4 with the extension 12 disposed on the opposite side thereof (see Fig. 2), when the forward end of the shank 8 is then disposed against the paper 2 and the nail driven through the paper and into the 40 sheathing boards 1 until the lower end of the spacing element 10 seats against the paper and the nail projected through the coils 11 with the head of the nail engaging the wire 4, holding it down tightly upon the 45 upper member of the coils.

After the nail has been driven down through the coils 11 as far as it can go, the extension 12 is struck downwardly and bent over upon the wire 4 thereby assisting the 50 head 9 in permanently clamping the wire 4 upon the spacing element. In practice it will be found that when driving the nail the hammer may be caused to engage and bend the extension 12 by the same blows 55 required to project the nail into the sheathing boards.

In the modification illustrated in Fig. 12, the head of the nail is diametrically enlarged and overlaps a portion of the extension 12 thereby causing the extension to be automatically forced down upon the wire 4 by the downward movement of the head of the nail.

It will be observed that in Figs. 4, 5, 6 and 7, the head 9 is shown disposed a slight

distance upwardly from the grille wire 4. It is intended, however, in the preferred form of the bracket, that the head, when the nail is driven into the sheathing as far as it is intended to go, shall seat directly on the grille wire and hold the same down firmly against the upper coil of the spacing element.

I claim:—

1. In means of the character described, a 75 grille bracket comprising, a nail element having a head at its upper end, and a spacing element formed of a length of wire wrapped around said nail element and having an extension at its upper end, said 80 spacing element adapted to coact with said head for holding a grille wire on said spacing element between said extension and said nail element.

2. In means of the character described, a 85 grille bracket comprising, a nail element having a head at its upper end, and a spacing element encircling an intermediate portion of said nail element and carried thereby, said spacing element having an upwardly projecting extension at its upper end, said 90 spacing element operatively slidable along on said nail element for engaging and holding a grille wire against the lower side of said head, said extension projecting upwardly along one side of said grille wire for limiting its movement on said spacing element in one direction.

3. In wall construction of the character described, a grille bracket comprising a nail element having a head at its upper end, and a spacing element embodying a length of wire formed into a plurality of coils wrapped around an intermediate portion of said nail element and carried thereon, said spacing element operatively vertically slid- 100 able along on said nail element for causing one of said coils to engage a grille wire for holding it permanently against the lower side of said head.

4. In means of the character described, a 105 grille bracket comprising a nail element having a nail head at its upper end, and a spacing element embodying a plurality of coils of wire encircling an intermediate portion of said nail element, one or more of said coils embracing said nail element with sufficient diametrical contractile tension to lock said spacing element thereon against normal vertical movement relative thereto, 110 said spacing element operatively vertically slid- 115 able on said nail element for engaging a grille wire for holding it permanently against the lower side of said head, one of said coils having an extension adapted to engage the upper side of said grille wire for holding it against movement in one direction.

5. In means of the character described, a 120 grille bracket comprising a nail element and a spacing element, said spacing element com- 125

prising a length of wire bent to form a plurality of coils wrapped on and around said nail element in serial order, one of the free ends of said length of wire forming an extension on the upper one of said coils, said extension adapted to engage and hold a grille wire on said upper coil, said nail element

having a head at its upper end adapted to engage said extension for holding it on said grille wire.

In testimony of the foregoing being my own, I have hereunto affixed my signature this 2nd day of December, 1922.

GEORGE F. VOIGHT.
